UNITED STATES PATENT OFFICE.

AXEL WELIN AND ARTHUR WILLIAM DAVIS, OF LONDON, ENGLAND, SAID WELIN
ASSIGNOR, BY MESNE ASSIGNMENTS, OF HIS ENTIRE RIGHT TO WELIN DAVIT &
BOAT CORPORATION, A CORPORATION OF NEW YORK.

SHIP'S DAVIT.

Application filed August 16, 1919. Serial No. 317,980.

(GRANTED UNDER THE PROVISIONS OF THE ACT OF MARCH 3, 1921, 41 STAT. L., 1313.)

To all whom it may concern:

Be it known that we, AXEL WELIN and ARTHUR WILLIAM DAVIS, subjects of the King of Sweden and of the King of Great Britain and Ireland, respectively, and both residents of London, E. C., England, have invented certain new and useful Improvements in Ship's Davits (for which applications have been filed in England August 1st, 1918, Patent No. 130,470), of which the following is a specification.

The primary object of this invention is to provide a pivotally-mounted davit comprising two relatively movable parts, one of which parts carries the other and is adapted to swing in a vertical plane to opposite sides of its pivot and the other part is adapted to move relatively to the carrier part and extend further inboard and outboard than said carrier part, thus procuring maximum out-reach and inboard extension and enabling a boat to be swung inboard and outboard without any torsional strain on the davit and a minimum of stress on the actuating mechanism thereof.

More particularly this invention comprises a base part having a long socket and pivoted on the deck of a vessel to swing to inboard and outboard positions which incline in opposite directions to the perpendicular position, and an arm part mounted in and rotatable axially in said socket and having an overhanging portion from which the boat is suspended and which is caused to travel in a substantially horizontal direction simultaneously with the vertical swinging of the said base part, which vertical swinging is preferably accomplished by suitable operating mechanism.

In the preferred embodiment of our invention, the base part is provided with a long socket and is pivoted on a horizontal pivot mounted on the deck of a vessel to move in a vertical plane about said pivot by operating mechanism comprising a link attached at one end to the top of the base part and at its other end having a pivotal connection with an arm fast with an arculate plate provided with a segmental rack meshing with a pinion on a shaft mounted in an elevated position in a vertically disposed frame; and said base part carries an arm part comprising a substantially straight

lower portion dropped into said socket and free to turn axially therein, and an upper curved overhanging portion, from which the load or boat is suspended.

Other objects of this invention will be in part obvious from the annexed drawings and in part indicated in connection therewith by the following analysis of this invention.

This invention accordingly also consists in the features of construction, combinations of parts, and in the unique relationship of the members and in the relative proportioning and disposition thereof, all as more completely outlined in the following specification and in said drawings.

To enable others skilled in the art so fully to comprehend the underlying features of our invention that they may embody the same by numerous modifications in structure and relationship of parts contemplated by this invention, drawings depicting a preferred form have been annexed as a part of this disclosure, and in such drawings like characters of reference denote corresponding parts throughout all the views, of which:—

Fig. 1 is a side elevation of a davit in inboard position with a boat suspended therefrom;

Fig. 2 is a similar view of a davit in its outboard position;

Fig. 3 is an elevation of a davit and suspended boat looking outboard;

Fig. 4 is a rear elevation of the device shown in Figs. 1 and 2, part of the davit arm being broken away; and

Fig. 5 is a fragmentary view partly in section of the actuating mechanism and arm in extended position.

Referring now to these drawings, 1 indicates a davit formed of a base part 2 adapted to swing in a vertical plane to inclined positions on opposite sides of a position perpendicular to the deck 3 and an arm 4 carried by said base part and movable axially in relation thereto. Said base part 2 is provided with a long socket 2^a and the arm part 4 comprises a straight lower portion 4^a which is dropped into said socket and an upper curved overhanging portion 4^b from which the boat is suspended and which is adapted simultaneously with the ver-

tical swinging of the base part to swing horizontally to opposite sides of the inclined planes which coincide with the axis of said base part when in its extreme positions. As illustrated, the vertically-swinging base part is pivoted on a horizontal pivot 5 mounted on the deck and disposed contiguous to and parallel with the side of the vessel; and the arm part comprises a round bar having a lower straight portion dropped into said socket and adapted to turn freely about its axis in said socket which forms a bearing therefor and an upper, curved overhanging portion to the end of which the load comprising the boat 6 is attached.

As illustrated, the base part 2 is so swung in a vertical plane about its pivot 5 by operating mechanism comprising a link 7 pivoted at one of its ends as at 7^a to the upper end of the said socketed base part 2, and pivotally connected at its opposite end, as at 8, to an arm 9^a fast with an arcuate plate 9 mounted on a spindle 10 in a frame 11. The plate 9 is provided with an internal segmental rack 12 meshing with a pinion 13 on a spindle 14 mounted in suitable bearings in an elevated position in said frame 11. The spindle 14 may be rotated in any suitable manner and, as shown, has fast upon it a worm wheel 15 meshing with a worm 16 on a shaft 17 also supported in said frame and having a squared end adapted to fit into the socket of a crank or like device.

It may, under certain unusual conditions, be desirable when the davit is in inboard position to temporarily fix the arm part against rotation in its socket, and for this purpose we preferably provide registering holes 18 and 19 in the said parts and insert a pin 20 therein. Under ordinary conditions, however, the use of such a pin is unnecessary.

It will be obvious that when the shaft 15 is rotated in one direction the base part will be swung about its pivot 5 in a vertical plane from its inboard position, which is inclined inwardly from a position perpendicular to the deck of a vessel, to its outboard position, which is inclined in the opposite direction from said perpendicular, and that during this movement the rotatable arm part will be caused to rotate about its axis so that the overhanging portion thereof will be caused to swing horizontally and to assume positions on opposite sides of inclined planes intersecting the axis of the vertically swinging part of the davit when the same is in its extreme positions, thus permitting a more extended movement of the top of the davit and a consequent greater relative outreach than would be possible with an overhanging part fixed in relation to the vertical swinging part.

It will be seen furthermore that the rota-

tion and horizontal swinging in combination with the vertical swinging will enable the load to be moved with less torsional strain on the davit arm than would be possible with relatively fixed parts, and furthermore that the stress on the operating mechanism is minimized.

In Figs. 1 to 2 a davit is shown attached to one end of a lifeboat 6 and mounted on the deck to have its straight part swing in a vertical plane beyond the end of the lifeboat. This davit, of course, comprises one of a pair of davits, the other member of which is similarly mounted and connected to the opposite end of the boat, so that the pair are spaced apart a distance greater than the length of the boat and are so arranged as to permit a boat to be moved by the actuating mechanism from its supports and swung outwardly between the said straight parts in parallel relationship to the side of the vessel and without manual handling of the boat and without the zigzagging of the boat usually necessary with round bar davits.

Having described our invention, we claim:

1. In a davit, the combination with a base part having a socket and pivoted at its lower end on the deck of a vessel and adapted to swing in a vertical plane only to opposite sides of a perpendicular to the deck at its pivoted point, of an arm part having a straight portion mounted in said socket to rotate freely therein and an overhanging portion adapted to swing horizontally to opposite sides of inclined planes coinciding with the axis of said base part in its two extreme positions; and actuating mechanism for swinging the base part to cause a simultaneous horizontal swinging of the said overhanging portion and a movement of the boat to inboard and outboard positions, said actuating mechanism being mounted on the deck and having a connection with the upper end of said base part.
2. In a davit, the combination with a base part having a socket and pivoted at its lower end on the deck of a vessel and adapted to swing in a vertical plane only into inclined positions on opposite sides of a perpendicular to the deck at its pivoted point, of an arm part having a straight portion mounted in said socket to rotate freely therein, an overhanging portion adapted to swing horizontally to opposite sides of the inclined planes coinciding with the axis of said base part in its two extreme positions, and actuating mechanism mounted inboard of said socket for swinging said base part vertically to cause a simultaneous horizontal swinging of the said overhanging portion and a movement of the boat to inboard and outboard positions, respectively, said actuating mechanism comprising a link

pivoted to said base part contiguous to the upper end thereof and between the pivot and top of the davit, an arm mounted in an elevated position to turn in the arc of a circle and connected to said link and means for turning said arm to swing the davit.

3. In a davit, the combination with a base part having a socket and pivoted at its lower end on the deck of a vessel and adapted to swing in a vertical plane only into inclined positions on opposite sides of a perpendicular to the deck at its pivoted point, of an arm part having a straight portion mounted in said socket to rotate freely therein, and an overhanging portion adapted to swing horizontally to opposite sides of the inclined planes coinciding with the axis of said base part in its two extreme positions, and actuating mechanism mounted inboard of said socket for swinging said base part vertically to cause a simultaneous horizontal swinging of the said overhanging portion and a movement of the boat to inboard and outboard positions, respectively, said actuating mechanism comprising a link pivoted to said base part contiguous to the upper end thereof between the pivot and top of the davit, an arm mounted in an elevated position to turn in the arc of a circle and connected to said link and provided with a segmental rack, a pinion meshing with said rack and a worm gear for rotating said pinion.
4. In a davit, the combination with a base part having a socket and pivoted at its lower end on the deck of a vessel and

adapted to swing in a vertical plane only into inclined positions on opposite sides of a perpendicular to the deck at its pivoted point, of an arm part having a straight portion mounted in said socket to rotate freely therein, and an overhanging portion adapted to swing horizontally to opposite sides of the inclined planes coinciding with the axis of said base part in its two extreme positions, 40 actuating mechanism mounted inboard of said socket for swinging said base part vertically to cause a simultaneous horizontal swinging of the said overhanging portion and a movement of the boat to inboard and 45 outboard positions, respectively, said actuating mechanism comprising a link pivoted to said base part contiguous to the upper end thereof between the pivot and top of the davit, an arm mounted in an elevated 50 position to turn in the arc of a circle and connected to said link and provided with a segmental rack, a pinion meshing with said rack and a worm gear for rotating said pinion. 55

In witness whereof, we have signed our names to the foregoing specification in the presence of two subscribing witnesses.
